(57) **CLAIM**

An ornamental design for a gearbox assembly for an axle, as shown and described.

DESCRIPTION

FIG. 1 is a front perspective view of a gearbox assembly for an axle;

FIG. 2 is a top plan view of the gearbox of FIG. 1;

FIG. 3 is a bottom plan view of the gearbox of FIG. 1;

FIG. 4 is a front elevational view of the gearbox of FIG. 1;

FIG. 5 is a rear elevational view of the gearbox of FIG. 1;

FIG. 6 is a right side elevational view of the gearbox of FIG. 1; and,

FIG. 7 is a left side elevational view of the gearbox of FIG. 1.

The broken lines, depicted as dot-dot-dot lines, are included for the purpose of illustrating the axle and/or portion(s) of the gearbox assembly that form no part of the claimed design.
